DISPLAY RACK

Francis J. Galassi, Boston, Mass.

Application January 13, 1958, Serial No. 49,205

Term of patent 14 years

(Cl. D80—9)

Fig. 1.

Fig. 2.

Fig. 3.

Fig. 1 is a perspective view of a display rack embodying my new design;

Fig. 2 is a top plan view; and

Fig. 3 is a side elevational view thereof.

The rear of said holder is substantially plain.

The side not shown is substantially the same as the side shown in Fig. 3.

I claim:

The ornamental design for a display rack, substantially as shown and described.
